CLAIM

The ornamental design for a shopper call box, as shown and described.

DESCRIPTION

FIG. 1 is a perspective view of a shopper call box, illustrating the invention in a wall-mount configuration, showing my new design;

FIG. 2 is a perspective view of a shopper call box shown in an alternate table-top configuration;

FIG. 3 is a front elevational view of the invention, illustrating the invention in the wall-mount configuration;

FIG. 4 is a right-side elevational view of the invention, illustrating the invention in the wall-mount configuration, the left-side elevational view being a mirror image thereof;

FIG. 5 is a top plan view of the invention, illustrating the invention in the wall-mount configuration; and,

FIG. 6 is a bottom plan view of the invention, illustrating the invention in the wall-mount configuration.

The rear elevational view is not visible during normal use, in either the wall-mount configuration or the table-top configuration, and constitutes no part of the claimed design.
